DECK LID LOCK

Ralph H. Wise, Detroit, Mich., assignor to Ternstedt Manufacturing Company, Detroit, Mich., a corporation of Michigan

Application October 11, 1939, Serial No. 299,005

5 Claims. (Cl. 292—97)

This invention relates to a lock and more particularly a lock for the deck lid of an automotive vehicle.

As is well-known, the deck lid (often called the trunk lid) of an automobile body is made of thin sheet steel and hinged at its upper forward edge to swing up and down about a horizontal axis. The deck lid follows the rearward and downward curvature of the body. Heretofore it has been common practice to lock the deck lid by means of locks positioned along the lower side edges of the lid and having bolts which project beyond the side edges of the lid to interengage keepers on the side edges of the rear deck opening. This type of latch draws the lower or rear portion of the deck lid inwardly toward the deck but not downwardly and because of this often places the lid under lengthwise compression which causes it to wrinkle or buckle slightly. This disadvantage could be eliminated by making the deck lid of heavier gauge sheet steel. However, it is the object of this invention to produce a deck lid lock which will obviate the above-mentioned disadvantage and lock the lid without causing wrinkling regardless of the gauge of the sheet metal lid. This object has been achieved by means of a latch arranged to draw the lid not only inwardly but downwardly so that when latched the deck lid is placed under tension or stressed longitudinally of the lid in a direction away from the hinges and there is no tendency of the latch to press the lid toward the hinges which causes wrinkling.

In the drawings:

Fig. 1 shows a vertical section through the deck lid lock with a fragmentary showing of the deck lid and deck opening.

Fig. 2 is an inside elevation of the deck lid lock.

Fig. 3 is an inside fragmentary elevation of the deck lid showing a deck lid locking system consisting of two locks.

Fig. 4 is a vertical section along the line 4—4 of Fig. 3.

Fig. 5 is a vertical section along the line 5—5 of Fig. 3.

Referring more particularly to the drawings there is shown a deck lid 1 for closing the opening in the deck 2 of an automobile body. The deck lid 1 is hinged along its upper edge in the conventional manner.

The deck lid is provided with the usual handle 3 fixed on the spindle 4 which is journaled in the die-cast housing 5 fixed to the deck lid. The inner end of the spindle 4 is also rotatably supported in the bracket 6 which is fixed to the inside panel 7 of the deck lid. A rollback in the form of a crank 8 is fixed on the inner end of the spindle 4. The outer end of the rollback 8 is connected to the bolt 9 by a connecting rod

10, one end of which is pivotally connected with the rollback 8 in the opening 11 and the other end of which is pivotally connected with the bolt 9 in the opening 12.

5 The bolt 9 is provided with a head portion 13 and an arcuate body portion 14 which slidably interengages a correspondingly arcuate guide 15. As shown, particularly in Fig. 2, the arcuate body portion of the bolt 14 takes the form of a channel section which is slidably telescoped within the arcuate guide 15 also of channel section. The bolt is provided with an elongated slot 50 through which spindle 4 projects. The slot 50 permits the bolt to slide relative to spindle 4. The guide 15 is welded or otherwise fixed to the bracket 6. The bolt head 13 is arranged to interengage the keeper 16 which is fixed to the lower horizontal edge 17 of the deck opening 18.

A bracket in the form of a stamping 19 having 20 side flanges 20 is secured by bolts 21 to the inner panel 7 of the deck so that it straddles the bolt 9, that is, so that the side flanges 20 are positioned on opposite sides of the bolt. This flanged bracket 19 effectively prevents access to the bolt by means of a tire iron or other tool which might be inserted between the lower edge 22 of the deck lid and the gutter 23.

The lock is shown in locked position in the full lines, Figs. 1 and 2. It should be noted that in 30 the locked position (Fig. 2) the rollback 8 is slightly over center and the side edge 24 of the rollback abuts the adjacent side wall 25 of the guide 15 to prevent further counterclockwise rotation of the rollback 8. In this position the bolt 35 9 cooperates with the keeper 16 to pull the deck lid downwardly and thereby stress the same longitudinally.

To release the bolt the handle 3 is turned to 40 rotate the rollback 8 clockwise to the dotted line position shown in Figs. 1 and 2. The rollback 8 acting through the connecting rod 10 pushes the bolt 9 downwardly and as the bolt slides in the arcuate guide 15, the arcuate guide directs the bolt downwardly and outwardly in an arcuate 45 path to disengage the same from the keeper 16. Further rotation of the handle 3 will slide the bolt 9 downward and outwardly to a position beyond the dotted line position whereby the deck lid will be freed to be opened. It is to be understood that the radius of arcuate guide 15 and the relative size and position of the parts is such that when the bolt 9 is fully extended (not shown) the parts will not interfere with each other and the deck lid may be freely opened.

55 In latching of the deck the reverse of this movement takes place, that is, as the rollback is rotated counterclockwise from the dotted line position, Fig. 2, the bolt 9 travels upwardly and inwardly toward the keeper from the dotted line to the full line position shown in Fig. 1 until the

bolt head 13 interengages keeper 16 whereupon further counterclockwise rotation of the rollback 8 draws the deck lid downwardly and inwardly toward the deck.

In Figs. 3 to 5 a modified form of the invention is shown in which the deck lid 1 carries a set of locks 30 and 31 positioned along the lower bottom edge of the deck lid on opposite sides of center. The locks 30 and 31 are identical with the principal form of lock described above except that the connecting rod 10 is operated by a crank 32 which is journaled in ears 33 and 34 struck out of the arcuate guide 15. The cranks 32 are formed in the opposite ends of a rod 35 which is journaled in the eyes 37 and 38 formed in the bracket 36. The bracket 36 is fixed to the inner panel 7 of the deck lid 1. The inner end of the deck lid handle spindle 4 is rotatably supported in the bracket 36. A crank 39 is fixed to the inner end of the spindle 4. A bracket 40 is pivotally mounted on the crank 39 and interengages the crank portion 41 in the elongated slot 42. The mounting of the rod 35 on the bracket 36, the configuration of the crank 41 and its connections 40 and 39 with the deck lid handle 3 are identical with those shown in the Rhein and Cooley Patent 2,135,625, to which reference may be had if further details of the same are desired.

As shown in the full lines, Figs. 3 to 5, the deck lid is locked. At this time the bolts 9 are interengaged with their respective keepers 16 and the cranks 32 have been swung clockwise, Fig. 4, slightly over center so that the connecting rods 10 abut the inside face of the bolt as at 43. To release the bolts the handle 3 is turned to rotate the crank 39 counterclockwise, Fig. 3. The crank 39 operating through the rod 35 causes the cranks 32 to rotate counterclockwise, Fig. 4, from the full line to the dotted line position thus sliding the bolts downwardly and outwardly from the keepers to disengage the same from their respective keepers.

Very often, due, for example, to a protuberant weatherstrip, the deck lid 1, prior to latching, will not close completely. In such case the latch bolt 13 will engage the keeper 16 and draw the deck lid downwardly and inwardly to closed position. Thus one of the advantages of this lock is that if the deck lid is not completely closed before latching, then the latch bolt 9 will cooperate with the keeper 16 to draw the deck lid closed.

I claim:

1. A lock comprising in combination a bolt curved longitudinally and provided with a hooked end, a correspondingly longitudinally curved guide for slidably supporting the bolt, the said bolt having an elongated slot, a rotatable handle spindle projecting through the bolt in the said slot, a crank on said spindle, a connecting link between the crank and the bolt whereby rotation of the handle spindle slides the bolt in its curved guide and the said crank being provided with an over center position whereby the bolt may be retained in a locked position.

2. In an automobile having a deck member provided with an opening and a hinged lid member for closing the said opening, a lock mounted on one of said members comprising in combination a longitudinally arcuate bolt having a bolt

head in the form of a hook, a correspondingly arcuate guide for slidably supporting the said bolt, said arcuate guide and bolt having their convex side adjacent said members, means for sliding the said bolt in its guide, said bolt head being adapted to engage a keeper in the form of a hook carried by the other of said members and impart a longitudinal tension in said bolt whereby when the bolt is slid into interengagement with its keeper it travels along an arcuate path and draws the deck lid inwardly toward the deck and stresses the same longitudinally toward said keeper to prevent wrinkling of the lid.

3. In an automobile having a deck member provided with an opening and a hinged lid member for closing the said opening, a lock mounted on one of said members opposite the hinged edge of said lid comprising in combination a longitudinally arcuate bolt having a bolt head in the form of a hook, a correspondingly arcuate guide for slidably supporting the said bolt, a crank, a link connecting the bolt and crank whereby turning of said crank slides the bolt, said bolt head being adapted to engage a keeper in the form of a hook carried by the other of said members whereby when the bolt is slid into interengagement with its keeper it travels along an arcuate path and draws the deck lid inwardly toward the deck and stresses the same longitudinally toward said keeper to prevent wrinkling of the lid.

4. In an automobile having a deck member provided with an opening and a hinged lid member for closing the said opening, a lock mounted on one of said members opposite the hinged edge of said lid comprising in combination a longitudinally arcuate bolt having a bolt head in the form of a hook, a correspondingly arcuate guide for slidably supporting the said bolt, an elongated slot in the said bolt, a rotatable spindle projected through the slot in the said bolt at approximately right angles to the bolt, a crank fixed to the end of the said spindle, a link connecting the crank with the bolt whereby rotation of the spindle slides the bolt, said bolt head being adapted to engage a keeper in the form of a hook carried by the other of said members whereby when the bolt is slid into interengagement with its keeper it travels along an arcuate path and draws the deck lid inwardly toward the deck and stresses the same longitudinally toward said keeper.

5. In an automobile having a deck member with an opening and a hinged lid member for closing the same, a lock mounted on one of said members comprising a longitudinally arcuate bolt provided with a bolt head in the form of a hook, a correspondingly arcuate guide for slidably supporting the said bolt, manual means for sliding the said bolt in either direction in its guide, said bolt head being adapted to engage a keeper in the form of a hook carried by the other of said members and transmit manual force into a longitudinal tension in said bolt whereby when the bolt is slid into interengagement with its keeper it travels along an arcuate path and imparts a positive pressure to draw the deck lid inwardly toward the deck and stresses the same longitudinally toward said keeper to prevent wrinkling of the lid.

RALPH H. WISE.
